Primary Examiner — Michael C Stout

Assistant Examiner — Olivia B. El-Nemri

(74) Attorney, Agent, or Firm — Fitch, Even, Tabin &
Flannery LLP(57) CLAIM

The ornamental design for a bottle, as shown and described.

DESCRIPTIONFIG. 1 is a top, front perspective view of a bottle in accordance with our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures show portions of the bottle that form no part of the claimed design.1 Claim, 5 Drawing Sheets(56) References Cited
